(57) **CLAIM**

The ornamental design for an inhaler, as shown and described.

DESCRIPTION

Figure 1.1 is a front perspective view of the inhaler; Figure 1.2 is a front view of the inhaler, and back view being identical;

Figure 1.3 is a first side view of the inhaler, and the second side view being identical;

Figure 1.4 is a perspective view of the inhaler with the cap removed;

Figure 1.5 is a front view of the inhaler with the cap removed;

Figure 1.6 is a side view of the inhaler with the cap removed; Figure 1.7 is a top view of the inhaler with the cap removed; and

Figure 1.8 is a bottom view of the inhaler.

The design is the visual features of the inhaler, shown in solid lines in the figures. In the reproductions, the broken lines show portions of the inhaler that form no part of the claimed design.
